UNITED STATES PATENT OFFICE.

WILLIAM HAROLD BANCROFT, WILLIAM JACKSON LUND, AND MAURICE GODFREY HILL, OF LEICESTER, ENGLAND, ASSIGNEES TO UNITED SHOE MACHINERY CORPORATION, OF PATERSON, NEW JERSEY, A CORPORATION OF NEW JERSEY.

SHOE STIFFENER AND ART OF MANUFACTURING IT.

Application filed December 31, 1924, Serial No. 759,084, and in Great Britain January 22, 1924.

This invention relates to a method of and a machine for operating upon stiffeners for boots and shoes and to a completed stiffener.

5 It is desirable that box toes for use in certain kinds of shoes, and particularly for use in so-called "plain-toed" shoes which have no toe cap or tip, should be very flexible along their rear margins; since otherwise 10 an objectionable ridge is liable to appear across the toe of the finished shoe.

A box toe which is very largely used in the manufacture of shoes consists of a piece of fibrous material impregnated with a thermoplastic stiffener substance,—that is, with a substance such, for example, as a mixture of 90 per cent of rosin and 10 per cent of carnauba wax, which is normally stiff and resilient but may be rendered plastic or 20 molten by heat. The rear margins of these box toes are commonly skived to render said margins less bulky and more flexible, but the margins so treated have proved to be too stiff and inflexible to be used satisfactorily 25 in "plain-toed" shoes.

In one aspect, the invention comprises a method in which the impregnant substance, or at least the greater part of it, is squeezed out of a selected margin of the stiffener, 30 while said substance is sufficiently soft, by pressure applied progressively across the margin toward the edge thereof. Preferably the pressure is a rolling one; and, in the case of a thermoplastic stiffener, the impregnant substance is softened by being melted. By applying the pressure progressively from a locality in the body portion of the stiffener across the margin, said margin is thinned without the formation of 40 a ridge of pressed-out impregnant substance such as might occur if the pressure were applied, for example, progressively in the opposite direction.

In another aspect, the invention relates 45 to a machine for carrying out the method comprising a pair of co-operating rolls, one or both of which may be heated, one of said rolls having a stiffener-receiving matrix so located and of such shape and size that the 50 proper progressive rolling pressure will be applied to the margin of the blank. Preferably the matrix will be made somewhat smaller than the stiffener so that part of the margin of the stiffener will extend outside

the matrix in position to be pressed between 55 cylindrical portions of the rolls, such a construction resulting in the production of a stiffener the extreme margin of which is very pliable.

In still another aspect, the invention relates to a completed stiffener.

Referring now to the accompanying drawings,

Figure 1 is a view principally in cross-section of a portion of a machine for treating box toe blanks;

Figure 2 is a development of a portion of the surface of the matrix roll showing a box toe blank in place, but without having been operated upon;

Figure 3 is a cross-section on the line 3—3 of Figure 2 viewed in the direction indicated by the arrow; and

Figure 4 is a cross-section of a finished box toe.

The machine comprises two metal rolls 5 and 7 between which the box toes are fed, said rolls being chambered to permit steam to be passed through them to heat them as indicated by the small arrows in Figure 1. 80 The box toe blanks 100 to be treated are stacked in a magazine, the rear wall of which is made up of two parts 9 and 11, the part 9 being adjustable vertically to provide for box toe blanks of different thicknesses. A presser 13 rests upon the stack, and a feed slide 15 is reciprocated to feed the blanks one by one in proper timed relation to the rolls 5 and 7. Any suitable mechanism may be employed to rotate the 90 rolls and to operate the slide such, for example, as that shown in the patent to Scott No. 760,082.

The lower roll 7 is provided with a matrix 17. As shown in Figures 2 and 3, the matrix or recess 17 is cut with beveled edges all around, the bevel along the rear edge, as shown at 19, being of a comparatively long taper. Furthermore, the recess is of a size and shape to allow some measurable width 100 (say $1/4$ inch on blanks of medium size) of the rear margin of the blank to project beyond the corresponding edge 21 of the matrix and thus be gripped, as the rolls rotate, between cylindrical portions of the rolls. 105 Figure 1 shows a blank of which the rear edge is thus gripped, and Figure 4 shows the result, the rear edge portion of the blank

having been practically entirely freed of impregnant by the roll pressure. In Figure 3 the blank is shown fully laid into the matrix but without the resulting action of pressure upon its edges.

Spikes 22 are preferably placed in the matrix to prevent any possibility of the blank shifting relatively to the matrix during its passage between the rolls.

- 10 A scraper 23 is conveniently arranged against the under side of the matrix roll to remove the expressed impregnant; and, in order to secure regular delivery of the blanks from the rolls (the blanks being at this time 70 entirely limp owing to their heated condition), a tray 25 provided with an upstanding lip 27 is placed below and to the rear of the lower roll. As each blank emerges from the bite of the rolls, its leading edge tends to 75 part from the matrix and thus engages the lip of the tray at about the same instant that the rear edge of the blank leaves the bite. This causes the blank to fall over flat upon the tray with its rear edge away from the 80 rolls as shown by the blank 100 in Figure 1. The rear wall of the magazine may be insulated if desired, so as to keep the stack of blanks cold in order that they may be fed with due regularity into the bite of the rolls, 85 30 it being understood that the rolls are brought to a temperature sufficient fully to melt the impregnant in the blank as the blank passes between them.

By suitably shaping the matrix, the point 35 at which the margin-thinning-pressure between the rolls becomes effective can be accurately determined and the pressure can with nicety be increased as the back edge of the blank is gradually reached, so that a 40 very gradual increase in pliability of the blank towards its back edge can be attained. The use of a matrix recess also enables the thinning to be performed along a curved line following that of the edge of the blank itself, a result not obtainable by plain rolling 45 action conducted across a curved edge.

Provided adequate heat and pressure be employed, the method described above may be used with advantage to replace wholly the 50 skiving or similar treatment of the margin of blanks which has been hitherto considered essential. Not only is the margin so thinned more pliant than one obtained in the customary ways referred to, but, in so far as the 55 fibrous material has not been weakened by the removal of a part of it, the thinned edge is extremely strong and is to an unusual degree adapted to resist rupture by the strains to which the blank is subjected when 60 being lasted into the shoe. Such a substitution of skiving by hot-pressing, effected very conveniently in a matrix roll type of machine as shown, may be applied to the 65 whole of the periphery of the blank if desired and is obviously not limited in its ap-

plication to the back edge of the blank. In this connection it will be observed that the matrix of Figure 3 is bevelled off around the whole of its edge, the bevel being a short incline around the front and side edges of the 70 blank as compared with that along the rear edge since, although extreme flexibility is not necessary around the front and side edges, a thinning of the edge at these parts is generally desirable and can be obtained 75 simultaneously with the treatment of the rear edge of the blank without any additional expenditure of time or labor. It will be apparent, however, that the method above described may be employed to advantage up- 80 on blanks that, possibly on account of their being made of special material, have been skived.

Having thus described our invention, what we claim as new and desire to secure 85 by Letters Patent of the United States is:

1. The method of producing a thin pliable margin on a stiffener blank made of fibrous material impregnated with a stiffening substance which consists in applying 90 pressure progressively across the margin toward the edge thereof to express impregnant substance from the margin.

2. The method of producing a thin pliable margin on a stiffener blank made of fibrous material impregnated with a stiffening substance which consists in softening the substance and applying pressure progressively 95 across the margin toward the edge thereof to express impregnant substance from the margin. 100

3. The method of producing a thin pliable margin on a stiffener blank made of fibrous material impregnated with a thermoplastic substance which consists in melting the substance and applying pressure progressively 105 across the margin toward the edge with sufficient force to express impregnant substance from the margin.

4. The method of producing a thin pliable margin on a stiffener blank made of fibrous material impregnated with a thermoplastic substance which consists in melting the substance and applying rolling pressure 110 progressively across the margin toward the edge with sufficient force to express impregnant substance from the margin. 115

5. A machine for thinning a margin of a shoe stiffener made of a piece of fibrous material impregnated with a thermoplastic 120 stiffening substance having, in combination, a pair of co-operating rotary rolls, one of said rolls having a matrix, and means for heating the rolls to a temperature sufficient to melt the impregnant substance. 125

6. A machine for thinning a margin of a shoe stiffener made of a piece of fibrous material impregnated with a thermoplastic stiffening substance having, in combination, a pair of co-operating rotary rolls, one of

said rolls having a matrix, means for heating the rolls to a temperature sufficient to melt the impregnant substance, and means for feeding stiffeners to the rolls.

5 7. A machine for treating stiffeners made of a piece of fibrous material impregnated with a thermoplastic stiffening substance having, in combination, a pair of co-operating rotary rolls, one of said rolls having a 10 matrix, and means for heating the rolls to a temperature sufficient to melt the impregnant substance, the relative sizes of the matrix and a stiffener being such that a margin of the stiffener will extend outside the ma- 15 trix.

8. A machine for thinning a margin of a shoe stiffener made of a piece of fibrous material impregnated with a thermoplastic stiff-

fening substance having, in combination, a pair of co-operating rotary rolls, one of said rolls having a matrix the depth of the greater portion of which is substantially equal to the thickness of the stiffener, the depth of the matrix at a marginal portion thereof decreasing gradually toward the edge thereof so as to cause progressively increasing pressure to be applied to that portion of the stiffener which is received in said marginal portion, and means for heating one of said rolls. 20 25 30

In testimony whereof we have signed our names to this specification.
